UNITED STATES PATENT OFFICE.

CHARLES M. RUTAN, OF PATERSON, NEW JERSEY.

COOLING-CASKET FOR PRESERVING THE BODIES OF CHILDREN.

SPECIFICATION forming part of Letters Patent No. 293,361, dated February 12, 1884.

Application filed September 4, 1882. (No model.)

To all whom it may concern:

Be it known that I, CHARLES M. RUTAN, a citizen of the United States, residing at Paterson, Passaic county, State of New Jersey, have invented a new and useful Improvement in Caskets for Preserving the Bodies of Children, of which the following is a specification, reference being had to the accompanying drawings, forming a part thereof.

10 Preserving-caskets as now constructed are large and cumbersome, with only a small light of glass in the top, or with a top or lid composed of two plates of glass for exposing the body to view.

15 The object of my invention is to produce a child's preserving-casket the entire top of which is composed of a single plate of glass, and the use of which is confined to preserving the bodies of children exclusively, which will be hereinafter more fully explained.

20 Figure 1 of the drawings is a front view of the cooler. Fig. 2 is an end view of the same. Fig. 3 is a longitudinal section, showing construction and general arrangement of details; and Fig. 4 is a cross-section.

25 *a* represents a casket for preserving the bodies of children after death, and is provided with a main cover or lid, *b*, which cover or lid is suitably hinged to the body *a* by hinges *f*, and is provided with a plate of glass, *d*, which glass is arranged in a rabbet prepared therefor near the top of the cover *b*. The glass plate *d* is formed of one single piece, covering the entire surface of the upper portion of the cover *b*, and is secured in the rabbet by putty *e*. The cover *b* is provided with an exposing-lid, *c*, which lid is suitably hinged to the edge of the cover *b*. Above the single plate of glass *d* the

joint between the body *a* and cover or lid *b* is provided with an elastic fillet, *h*, said fillet 40 being arranged in a groove prepared therefor in the body *a* and cover *b*. The casket is provided with handles *s*. The interior of the casket is provided with a metal lining, *m*, having a faucet, *n*, racks or brackets *l*, cooling-frame 45 *g*, having handles *k*, and head-rest *i*.

In practice, the body to be preserved is placed on the cooling-frame *g*; the ice is placed in the space *p*; the frame *g* is lifted by the handles *k* and placed with the body on the 50 brackets *l*; the cover *b* is closed and secured by the catch. The elastic fillet prevents the tainted air from escaping from the interior of the casket, while the water is conducted by the faucet *n* to its receptacle. The cover *c* is closed. 55 When for any purpose the body is to be exposed, the exposing-lid *c* is raised, which action exposes the entire body to view by means of the unobstructed single plate of glass *d*.

I am aware that the lining *m*, faucet *n*, cooling-frame *g*, racks *l*, also covers having glass plates arranged therein, are old in preserving-caskets for adults, for which caskets I make no claim herein; but

65 I claim—

In a cooler for corpses of children, a lid, *b*, having full-length glass *d*, in combination with a cooling-board, *g*, vertically adjustable upon supports *l* within the cooler, whereby the full length of the corpse can be exposed to view at 70 a suitable distance below the glass, substantially as set forth.

CHARLES M. RUTAN.
